LOUNGE CHAIR

Johannes Luckhardt, Berlin-Dahlem, Germany,
assignor, by mesne assignments, to Norman P.
Martin and Otto L. Walter, as trustees of Beta
Trust, Lake Worth, Fla.

Application April 30, 1952, Serial No. 285,098

4 Claims. (Cl. 155—116)

1

This invention relates to articles of furniture and more particularly to lounge chairs.

An object of the present invention is to provide a lounge chair with a link system including a movable back-rest and a movable sitting structure which may be readily and conveniently brought into different positions.

A further object of the present invention is to provide a lounge chair with a movable back-rest and sitting structure which may be readily manufactured at low cost.

Another object of the invention is to improve on the construction of lounge chairs as now customarily made.

Other objects and structural details of the invention will be apparent from the following description when read in conjunction with the accompanying drawings forming part of this specification, wherein:

Fig. 1 is a side elevational view of a lounge chair according to the invention, and

Fig. 2 is a side elevational view of a lounge chair similar to that shown in Fig. 1, wherein, however, the back-rest and sitting structure of the lounge chair are in a reclined position.

Referring now to Figs. 1 and 2, 10 generally indicates a support having side frames connected with each other by transverse bars 12 in any suitable manner.

A back-rest 14 is swingably mounted on the support 10 at 16.

18 generally indicates a sitting structure comprising a seat portion 20 and a leg-rest portion 22 integral with each other. The rear end portion of the sitting structure 18 is pivotally connected with the back-rest 14 at 24.

On each side of the lounge chair a disk-like controlling member 26 is swingably mounted at 28 on a bar 30 rigidly connected with the front portion of the support 10. Of course, it is an obvious expedient to make said bar 30 integral with said support 10, thus incorporating said bar 30 into the front portion of said support.

One end of a controlling link 32 is pivotally connected with the controlling member 26 at the point 34 spaced from the pivotal connection 28 between the controlling member and the bar 30 rigid with the support 10. The other end of said controlling link is pivotally connected at 36 with the front end of the sitting structure 18.

2

One end of a guiding link 38 is pivotally connected with the controlling member 26 at the point 40 spaced from the pivotal connection 28 between the controlling member 26 and the bar 30 of the support 10. The other end of said guiding link 38 is pivotally connected at 42 with an intermediate portion of the sitting structure 18. According to the embodiment shown in Figs. 1 and 2, this pivotal connection 42 is located in the seat portion 20 of the sitting structure 18.

The pivotal connection 34 of the controlling link 32 with the controlling member 26 is spaced from the pivotal connection 40 of the guiding link 38 with said controlling member 26.

When the person resting on the chair leans the weight of his body against the back-rest, the movable members of the lounge chair may be readily brought from the sitting position shown in Fig. 1 into the reclined position shown in Fig. 2. On the other hand, upon slight pressure with the legs on the leg-rest 22, the person resting on the chair may readily return the movable members of the chair from the reclined position shown in Fig. 2 into the sitting position shown in Fig. 1.

I have described a preferred embodiment of my invention, but it is understood that this disclosure is for the purpose of illustration, and that various omissions and changes in shape, proportion and arrangement of parts, as well as the substitution of equivalent elements for the arrangements shown and described may be made without departing from the spirit and scope of the invention as set forth in the appended claims.

For example, stopping means may be arranged on the chair for limiting the end positions of the movable members of the chair, i. e. the sitting position and the extreme reclined position.

Furthermore, locking means could be arranged on the chair for holding the movable members of the chair in any desired position.

What I claim is:

1. A lounge chair, comprising in combination: a support, a back-rest pivoted to the rear portion of said support, a sitting structure including a seat and a leg-rest rigid with each other, the rear end portion of said sitting structure being pivoted to said back-rest, a controlling member pivotally connected with the front portion of said support, a controlling link pivoted at one of its ends to said controlling member at a point

spaced from the pivotal connection of the latter with the support, the other end of said controlling link being pivoted to the front portion of said sitting structure, and a guiding link pivoted at one of its ends to said controlling member at a point spaced from the pivotal connection of the latter with the support, the other end of said guiding link being pivoted to a point of the sitting structure intermediate the ends thereof.

2. In a lounge chair as claimed in claim 1, the 10 pivotal connection of the controlling member with the controlling link being spaced from the pivotal connection of the controlling member with the guiding link.

3. In a lounge chair as claimed in claim 1, said pivotal connection between the guiding link and the sitting structure being located in the seat portion of said sitting structure.

5. 4. In a lounge chair as claimed in claim 1, said support being in the shape of a rigid unit.
